UNITED STATES PATENT OFFICE.

HUGH R. ONEY AND LEWIS V. RANSOM, OF SISTERSVILLE, WEST VIRGINIA.

CIGAR-ROLLING MACHINE.

1,280,528.

Specification of Letters Patent.

Patented Oct. 1, 1918.

Application filed October 13, 1916. Serial No. 125,439.

To all whom it may concern:

Be it known that we, HUGH R. ONEY and LEWIS V. RANSOM, citizens of the United States, residing at Sistersville, in the county 5 of Tyler and State of West Virginia, have invented new and useful Improvements in Cigar-Rolling Machines, of which the following is a specification.

This invention relates to machines used 10 for rolling cigars, stogies and the like and which are generally known as cigar rolling machines.

The invention has for its object to produce a simple and efficient machine of improved construction to facilitate the application 15 of the wrapper to the bunch of a cigar, stogie or the like.

A further object of the invention is to produce a machine of the class described 20 embodying a power belt adapted to be actuated by the foot of the operator by means of suitable mechanism, a pocket belt driven by frictional contact with the power belt and adapted to form a pocket for the reception 25 of the bunch, and a pocket drum which is movably supported and over which the wrapper may be fed to the bunch.

A further object of the invention is to produce simple and improved mechanism 30 whereby the power belt will be driven in one direction when actuated by the operator by means of a pedal, said power belt being permitted to remain stationary on the return movement of the pedal during which 35 the finished product may be removed from the pocket and the unwrapped bunch substituted therefor.

A further object of the invention is to produce simple and efficient means for automatically adjusting the tension on the 40 pocket belt to produce a product of the proper dimensions.

With these and other ends in view which will readily appear as the nature of the 45 invention is better understood, the same consists in the improved construction and novel arrangement and combination of parts which will be hereinafter fully described and particularly pointed out in the claims.

50 In the accompanying drawings has been illustrated a simple and preferred form of the invention, it being, however, understood that no limitation is necessarily made to the precise structural details therein exhibited, but that changes, alterations and modifi-

cations within the scope of the claims may be resorted to when desired.

In the drawings—

Figure 1 is a top plan view of a machine constructed in accordance with the invention.

Fig. 2 is a side elevation of the same.

Fig. 3 is a longitudinal sectional view taken on the line 3—3 in Fig. 1.

Fig. 4 is a transverse sectional view taken 65 on the line 4—4 in Fig. 1.

Fig. 5 is a sectional detail view showing the pocket drum swung back to permit the insertion of a bunch.

Fig. 6 is a transverse sectional detail view 70 taken through the clutch devices for actuating the power belt.

Fig. 7 is a horizontal sectional detail view taken on the line 7—7 in Fig. 6.

Corresponding parts in the several figures 75 are denoted by like characters of reference.

The main frame of the improved machine which is of rectangular form is composed of side members 15, front and rear end members 16, 17, said frame being adapted to be supported on suitable legs or supports, parts of which have been shown at 18. Bearings are provided near the rearward end of the frame for a relatively large drum 19, said bearings, which are designated by 20, being supported 80 for longitudinal sliding movement in guides 21 which are provided with set screws 22, whereby longitudinal adjustment of the bearings may be effected. Supported for rotation relatively near the forward end of the 85 frame is a drum 23. A belt or apron 24, known as the power belt, is trained over the drums 19 and 23, it being understood that by adjustment of the bearing members 20 the said belt may be properly tensioned. 95

The inner side faces of the side members 15 are provided with longitudinally disposed guide cleats 25, whereby the clutch carriages 26 are supported and guided. The clutch carriages afford bearings for a roller 27 which will be known as the upper clutch roller; said carriages are also provided with slots 28 wherein a roller 29, which will be known as the lower clutch roller, is supported for rotation and also for vertical 100 movement. A yoke B, the limbs or side members of which, 30, are pivotally connected at their upper ends with the side members of the frame adjacent to the front of the latter, constitutes a pedal member, the 110

bridge piece 31 being adapted to be engaged by the foot of the operator. The limbs of the yoke are provided with lugs 32 with which braces or connecting rods 33 are pivotally connected, said braces being provided with bearings for the lower clutch roller.

It will be seen that when the yoke is swung or moved in a rearward direction by the foot of the operator, the lower clutch 10 roller will be lifted by the action of the braces until a portion of the lower lead of the power belt is clamped between the lower and upper clutch members. By a continued movement of the yoke the clutch carriages 15 will be caused to travel rearwardly in their respective guides, thus operating the power belt in such a manner as to cause the top lead of said belt to move in a forward direction. When the yoke is returned to its initial 20 position, the grip of the clutch rollers on the power belt will be released, and the forward movement of the yoke and related parts will be accomplished without moving the power belt.

25 Supported for rotation in the side members of the frame near the front end thereof is a roller 34 on the shaft of which is pivotally mounted the pocket drum D which is a trough-shaped member of approximately 30 semi-cylindrical form, the convex side of which is presented upwardly so as to extend above the top edges of the side members of the frame. It will be observed that the roller 34, while journaled in the side members of the frame, is practically located within the pocket drum, and said pocket drum carries a second roller 35, the shaft of which, 35 projects beyond the ends of the pocket drum so as to be normally supported on the 40 top edges of the side members of the frame, as clearly seen in Fig. 1. The drum D is provided with a downwardly and forwardly extending arm 37 which is connected by a spring 38 with the forward end portion of 45 the frame, said spring serving to move the pocket drum in a downward and forward direction until the end portions of the shaft 36, which constitute stop members, as above described, engage the top edges of the side members 50 of the frame. The pocket drum is equipped with a spring yoke 40 which is maintained in position by coiling portions of the limbs thereof on the end portions of the shaft 36, said coils being seen at 41, and 55 the end portions of the yoke being formed with hooks 42 engaging the end portions of the pocket drum. The bridge portion of the yoke 40 constitutes a handle, whereby the drum may be moved against the tension of 60 the spring 38, said bridge portion being, however, bent so that the middle portion thereof will constitute a holder 43 which slightly engages the top face of the drum and beneath which the wrapper may be fed. 65 The side members of the frame are pro-

vided intermediate the ends thereof with tubular uprights 44 provided in the inner faces thereof with slots 45, said uprights affording housings for coiled springs 46, the lower ends of which are provided with eyes 70 47 affording bearings for the shaft 48 of a roller 49 which is in this manner supported or suspended for vertical movement between the tubular uprights. The latter are connected together at their upper ends by a cross bar 50, and tension rods 51 and nuts 52 are provided for the springs 46. The pocket belt 53 is trained over the large drum 19, over the roller 29 and over the rollers 34 and 35 within the pocket drum, the last 80 mentioned roller, 35, which is carried by the pivotally supported pocket drum, serving to depress a portion of the pocket belt adjacent to the small drum 23 over which the power belt is trained, thereby forming a 85 pocket for the reception of the bunch which is to be wrapped. For the purpose of equalizing the tension on the pocket belt flat springs 54 are provided, said springs being secured on the top faces of the side 90 members of the frame with their free ends engaging and bearing against the lower side of the shaft of the spring supported roller 49. Springs 54 coöperate with springs 46 and serve to maintain roller 49 against undue vibration. It will be observed that the pocket belt, which is constantly under tension, is also constantly in frictional engagement with that portion of the power belt which is trained over the large drum 19, 100 causing the said pocket belt to be frictionally driven by the power belt when the latter is actuated.

Supported on the frame at the front end thereof is a table 55, the rear end of which overhangs the convex portion of the pocket drum, the parts being so arranged and proportioned that the swinging movement of the pocket drum will not be interfered with, while at the same time the rear edge of the table 55 practically contacts with the face of the drum so as to prevent material from dropping between the table and the drum. The said table forms a support for the material used by the workman.

It may be stated that in the preferred construction of the machine the several drums and rollers over which the power belt and the pocket belt are trained are preferably coated or faced with rubber or other suitable yielding material. This principally applies to the drum 23 and to the roller 35 between which the pocket for the reception of the bunch is formed.

In the operation of this device, the operator places the bunch which has been previously formed in the loop or pocket formed in the belt 53 between the drum 23 and the roller 35, the pocket drum having been previously rocked in a forward direction 130

against the tension of the spring 38 to permit the bunch to be conveniently inserted. One finger of the operator engages the central portion 43 of member 40 as shown in Fig. 5 when rocking drum D in the manner specified. The pocket drum having been restored to its initial position, and the wrapper having been inserted beneath device 43 the operator now by actuating the pedal-yoke B imparts motion to the power belt and incidentally to the pocket belt which is frictionally actuated thereby, at the same time presenting and properly feeding the wrapper to the bunch over the smooth and convex top face of the drum. By the rotation of the bunch caused by the movement of the pocket belt the wrapper, which is guided by the operator, will be quickly rolled about the bunch which may now be removed by the operator, being released by swinging the top drum forwardly, as before. The product may be finished and tipped by the operator before placing another bunch in the machine, or it may be passed to another workman for finishing.

The improved machine, as will be seen from the foregoing description, is extremely simple in construction, and it has been found thoroughly effective and useful for the purposes for which it is provided.

Having thus described the invention, what is claimed as new, is:

1. In a machine of the class described, a pocket belt, a power belt and mounting means therefor, means for gripping and moving the power belt longitudinally, a rocking member, rollers mounted therein and around which the pocket belt is trained, said belt last named inclosing the power belt, and said rocking member acting to throw the pocket belt into engagement with the power belt.

2. In a machine of the class described, a frame, drums carried thereby, a power belt trained over the drums, a pair of carriages guided for longitudinal movement with respect to the frame, one at each side of the power belt, clutch rollers mounted in the carriages, one at each side of the bottom lead of the belt, and means for actuating the clutch rollers and the carriages to impart movement in one direction to the power belt.

3. In a machine of the class described, a frame, drums carried thereby, a power belt trained over the drums, carriages guided for longitudinal movement on the frame, one at each side of the power belt, said carriages having slots, a clutch roller supported for rotation in the carriages adjacent to one face of the bottom lead of the belt, a second clutch roller supported adjacent to the other side of the bottom lead of the belt and having its shaft terminally extended into the slots of the carriages, a pedal-yoke con-

nected pivotally with the frame, and braces connected pivotally with the limbs of said yoke, said braces having bearings for the shaft of the last mentioned clutch roller.

4. In a machine of the class described, a frame, drums carried thereby, a power belt trained over the drums, carriages mounted for longitudinal movement adjacent to the sides of the belt, clutch rollers supported by the carriages, one adjacent to each face of the bottom lead of the belt and one of said clutch rollers being movable toward and from the other clutch roller to grip and release the belt, and swingingly supported means for actuating the carriages and the movable clutch roller, said means including braces having bearings for the shaft of the said movable clutch roller.

5. In a machine of the class described, a frame, a suitably supported power belt, means for intermittently actuating the same, said means comprising a plurality of rollers one of which is movable toward and away from the other whereby the belt is gripped by the rollers and caused to travel longitudinally, a pocket belt surrounding the power belt and frictionally contacting with portions thereof to be driven thereby, and rollers carried by the frame and over which the pocket belt is guided to space portions thereof from the power belt, one of said guide rollers being resiliently supported to maintain the pocket belt under proper tension.

6. In a machine of the class described, a frame, a power belt, means for intermittently operating said belt, slotted tubular uprights carried by the frame, a guide roller extending between said uprights, tension springs housed in the uprights and having eyes in which the roller is supported for rotation, a second guide roller carried between the side members of the frame near the front end thereof, a pocket belt surrounding the power belt and guided over the guide rollers, and means for depressing a portion of the pocket belt to form a pocket.

7. In a machine of the class described, a frame, a power belt, means for intermittently actuating the same, a pocket belt surrounding the power belt and contacting with a portion thereof to be driven thereby and spaced from other portions thereof, the spacing means including a guide roller and a tension roller, a pocket drum mounted to rock toward and away from the power belt, and a roller carried by the pocket drum and over which the pocket belt is guided.

8. In a machine of the class described, a frame, a power belt, means for intermittently actuating the same, a pocket belt surrounding the power belt and contacting with a portion thereof to be driven thereby and spaced from other portions thereof,

the spacing means including a guide roller and a tension roller, a pocket drum mounted to rock toward and away from the power belt, and a roller carried by the pocket drum and over which the pocket belt is guided, said power belt having a supporting drum at the forward end thereof, and said pocket drum being spring actuated in the direction of said supporting drum to form a pocket in the pocket belt between said supporting drum and the roller carried by the pocket drum.

9. In a machine of the class described, a frame, an intermittently operable power belt, a pocket belt surrounding the power belt and driven frictionally thereby, supporting means for the pocket belt including a tension roller and a guide roller, a spring actuated pocket drum mounted to rock toward and away from the power belt, and a roller carried by the pocket drum and having a shaft protruding beyond the ends thereof to form stop members engaging the side members of the frame.

25 10. In a machine of the class described, a frame, an intermittently operable power belt, a pocket belt surrounding the power belt and driven frictionally thereby, supporting means for the pocket belt including a tension roller and a guide roller, a spring actuated pocket drum mounted to rock toward and away from the power belt, and

a roller carried by the pocket drum and having a shaft protruding beyond the ends thereof to form stop members engaging the side members of the frame, and a resilient yoke having coils engaging the protruding end portions of the shaft, said yoke having an intermediate portion engaging the convex top face of the pocket drum.

11. In a machine of the class described, a power belt, an intermittently movable friction driven pocket belt, supporting means for the same including a guide roller, a spring actuated pocket drum mounted to rock toward and away from the power belt, and a roller carried by and housed within the pocket drum.

12. In a machine of the class described, a power belt, an intermittently movable friction driven pocket belt, supporting means for the same including a guide roller, a spring actuated pocket drum mounted to rock toward and away from the power belt, and a roller carried by and housed within the pocket drum; said pocket drum consisting of a semi-cylindrical hollow structure; and a table engaging the convex face of the pocket drum.

In testimony whereof we affix our signatures.

HUGH R. ONEY.
LEWIS V. RANSOM.
